UNITED STATES PATENT OFFICE.

GEORGES D'INFREVILLE, OF NEW YORK, N. Y., ASSIGNOR OF ONE-FOURTH
HIS RIGHT TO WILLIAM N. ARMSTRONG, OF SAME PLACE.

IMPROVEMENT IN DUPLEX TELEGRAPHS.

Specification forming part of Letters Patent No. **147,487**, dated February 17, 1874; application filed April 25, 1873.

To all whom it may concern:

Be it known that I, GEORGES D'INFREVILLE, residing at the city of New York, in the county and State of New York, have invented a new and simple Method of Adapting Duplex Transmission to an ordinary Telegraphic Line, of which the following is a specification:

The object of this invention is to obtain a simple method of sending messages simultaneously, over the same wire, in opposite directions, either between terminal, or terminal and way, or way and way, stations. It has, for a further object, the sending of messages, as above set forth, with the least possible change of instruments and dispositions already in use; and for this purpose, and for illustration, the Morse system is herein chosen.

My invention requires the following arrangements: First, in opposing to each other, through a telegraphic line, at its extremities, the similar poles of the terminal batteries, so that they have a common circuit, and neutralize each other; second, in using a single contact-key at each station in working the line for duplex transmission. The anvil of this key connects with the ground, while a wire from its lever is in junction with a proper point in the wire of the helices of the main electro-magnet, the purpose of which I will describe hereafter; third, the exposing of one or more layers or parts of the helices of one spool of the main electro-magnet, so that direct contact can be made, at any desirable point in the helices, with the wire from the lever of the key; fourth, a shunt-circuit of variable and proper resistance, one extremity of which is attached to the wire connecting the key with the helices above described, the other extremity being connected, when required, with one or the other end of the wire going out of the electro-magnet, as explained hereafter.

By way of explanation, I state that, in a common circuit, when the poles of two batteries are opposed, their effects are neutralized; but, if a wire connects the common circuit with the ground, two distinct circuits are at once made. Also, if one spool of a common electro-magnet be traversed by an electric current, and the other spool be traversed by a current

in an opposite direction, they tend to neutralize each other's effect, while either current, acting alone, would produce magnetization.

My invention consists in the combination and use of the above-mentioned opposing batteries, electro-magnets, single contact-keys, with shunt-circuit, if necessary, so that the depressing of the key at the sending-station divides the common circuit of the batteries hereinbefore described into two independent circuits—one of the distant and receiving station, through the line and sending-station, and the other a short circuit of the battery at the sending-station, the former recording signals at the receiving-station, and both circuits neutralizing each other's effects in the sending-station, so that its armature is not affected; and, also, by depressing simultaneously the keys at terminal stations, two distinct local and independent circuits are made at each station, and each station records only the signal of the other.

The circuit-reversers are here used in order to show how my system can be used with the common Morse plan, and the single transmitting and ordinary method used, by simply moving the circuit-reverser, and connecting the line and batteries in the usual way.

My system, when used alone on Morse's plan, would connect, through wire *e*, the electro-magnet and battery-pole *B*, dispensing with *X a b d*, and negative pole *A* would go directly to ground.

In the accompanying drawing, Figure 1 represents a plan view of the system, showing the arrangement for a line of three stations—two terminal and one way—all in the same circuit. The disposition is the same if more stations are used. Fig. 2 is a sectional view of the stations. Fig. 3 is a detail and end view of one coil of the main electro-magnet.

Similar letters of reference indicate corresponding parts.

The letter *A* represents the negative, and *B* the positive, pole of the main battery at terminal station *C*. The other terminal station, *D*, has the poles of its main battery represented by *E* for the negative, and *F* for the positive, pole. *G* is a way-station without any main battery. The poles of the batteries are con-

neected with the arms of the circuit-reversers X and X^2 .

The drawing shows the line ready for duplex transmission.

The circuit of the battery at station C is as follows: From the positive pole B through arm a of circuit-reverser X, conductor b , anvil of common key R, (used in single transmission,) circuit-closer d of the key R, conductor c , helices of the electro-magnet H, through line-wire I, and, if the cut-out g is open, as shown, at way-station G, through electro-magnet J and circuit-closer j , (of the common key for single transmission,) conductor l , again line I, helices of electro-magnet at terminal station D, conductor c^2 , circuit-closer d^2 , conductor b^2 , and conductor a^2 of circuit-closer X^2 , which is attached to the screw-post of the positive pole F, through battery at D, ground-wire N, ground-conductor N^2 , and other arm of circuit-reverser X, to negative pole A. Also, circuit from battery at station D is from positive pole F through a^2 b^2 d^2 c^2 , magnet L, line I, and way-station G, magnet H, wire c d b , arm a of circuit-reverser X, to positive pole B, through battery at C, other arm of circuit-reverser X, conductor N^2 , to ground, and N to negative pole E.

It will be noticed in the drawing that the Morse key, with circuit-closer, is shown in direct circuit in all the stations, so that, by merely changing the position of the circuit-reverser of either terminal station, the line can be worked on the closed-circuit system for simple transmission, as now in use, the relay-armatures being attracted when line is not worked.

Fig. 1 shows at station C a rheostat, O, in the shunt-circuit 1, connecting the battery through keys R and M^2 around the magnet H, the arm m being used to bring into circuit a greater or less amount of the resistance O. Similar dispositions are made at the other stations. At the way-stations movable arm of the rheostat can be brought in contact with one or the other extremity of the electro-magnet, as may be required, through a commutator or switch attached to the arm. In the position as shown in the drawing, with the batteries opposed and the key at rest, no current flows in the line sufficient to overcome the springs of the armatures, because, the circuit of both batteries being always closed, and the batteries being connected to the line so as to oppose each other, the currents become opposed to each other and neutralize the effect in the electro-magnets.

One condition of duplex telegraphy is, that any station shall send signals without affecting its own magnet and armature, although they are in the direct circuit. The operation is as follows: Let key M^2 , used for duplex transmission, be depressed at station C. At once the current from positive pole B at station C passes through conductors a b , circuit-closer of single transmission-key d , conductor c , entering the spool at the right side, in draw-

ing, of the electro-magnet H, running over a part of its helices, but leaving it where wire h^2 is attached to it, through h^2 , key M^2 , part of conductor N^2 , and returning through branch of circuit-reverser X to the negative pole of battery. The other current, from positive pole F at station D, being no longer opposed by current from B at station C, passes through conductors a^2 b^2 , circuit-closer d^2 , conductor c^2 , helices of electro-magnet L, magnetizing its cores, attracting its armature, recording signal of M^2 , through line I, magnet at way-stations, recording same signal by attracting armatures, then to and through a part of electro-magnet at station C to the junction of wire h^2 with helices; thence through wire h^2 , through key M^2 , conductor N^2 to the ground, back to negative pole E of battery at D, through part of N^2 , and circuit-reverser X^2 .

It will be noticed that the current from B, working in local circuit, and current from F use the wire h^2 , key M^2 , and part of conductor N^2 , in common, from junction with the helices as far as the circuit-reverser X. The key M^2 serves to conduct two currents.

While all the electro-magnets of the line have their armatures attracted by the current from D, the electro-magnet H at C, the sending-station, does not attract its armature, for it has been divided by wire h^2 into two parts, which are now traveled by opposite currents of different intensities. Each current tends to produce a magnetic polarity different from that of the other. If the two parts of the helices are so divided that the polarity which the strongest current, coming from the now local battery, tends to produce in going through the shortest part, nearly counterbalances or neutralizes the polarity which the weaker current, coming from the distant battery, tends to produce in going through the longer part, and in opposite direction, no appreciable magnetization will take place in the cores of the electro-magnet, and the armature of H will not be attracted. Thus one important condition of duplex telegraphy is secured.

The dividing of the helices into two parts, so that the current in one part shall neutralize properly the opposing current in the other part, is made by connecting the wire h^2 to the exposed layers of the electro-magnet at a point which the working of the line will determine. The proper connection is made when, on depressing the key at any station, its own armature is not affected, the other keys being at rest. If the key M at station D is also depressed alone, the results are the same. Its armature is not affected, but the armature of receiving-station is at work.

It thus appears that by this disposition of the line and instruments, one key alone being depressed, the sending-station records its signal at the receiving-station by receiving instead of sending a current, and allowing the current of the receiving-station its full force in recording.

I have shown the working of the current when one key only—for instance, M^2 —is depressed. The duplex transmission will now be shown. If, while the key M^2 is depressed, as above described, working the distant stations, with its own at rest, the key M at station D be now depressed, the current from positive pole F , at D ceases to pass through the line to C , because a short circuit is instantly established. The current runs from positive pole F through $a^2 d^2 e^2$, through part of magnet L , back through wire h and N , to negative pole. As this current, moving on a short circuit, no longer runs along wire I to magnet H , the neutralization existing at H when M^2 was alone depressed is destroyed, and its armature is at once attracted through the magnetization of local current at C , made by depressed key M^2 .

The currents of both batteries move in local circuits, because they meet the least resistance in that way; their circuit is not broken through the line. The very slight escape of electricity in H and L to the line, from the local circuits, still oppose each other. The armature at D , which was attracted by the depressed key M^2 , still remains depressed, because the current from F still runs through a part of magnet L , and with increased power, because it is on a short circuit. Stations C and D are now in the same condition. If, now, key M be raised, the condition of the current and working is again the same as when M^2 alone worked. The current from pole F again runs over line to H , neutralizes currents from B , and armature of H goes back, while armature at L remains attracted, as before, by the working of key M^2 . Thus the working of the armature at each terminal station is dependent upon and controlled by working of the key at opposite terminal station. Although way-station G has no main battery, it sends and receives messages in the same way. If the key P is depressed, the two currents from C and D cease to oppose each other, and go to the ground in common through key P and conductor 2 , back to their respective negative poles. For it is well known that if two batteries are opposed to each other in a line, a ground-wire at any point of the line will divide this line in two distinct circuits, each of which will operate without interfering with the other. The armature of H and of other way-stations, if any, are attracted by current from positive pole B , going to G ; and armatures at D and at other way-stations, if any, are attracted by current from positive pole F , going to G . The opposite currents, meeting in the electro-magnet at G , neutralize each other, so its own message is not recorded. The way-stations do not require a main battery. Station G does not require a main battery to transmit to or receive from C . It uses the main battery at D for its local neutralization, exactly as D uses it, only it is at a dis-

tance. Also, G will use the main battery of C for its local neutralization when it is signaling with D ; and G , in duplex transmission with D , will operate exactly as if was station C . This is an important part of my invention.

Thus any two stations, either terminal or way, or way and way, can perform duplex transmission. As above described, the wire h^1 is connected with a point in the helices of electro-magnet H , so as to effect neutralization of current. The desired point may not always be available, as it may be in the interior of the magnet.

The shunt-circuit will secure a finer adjustment, if needed. As described and adjusted, it draws off part of one of the currents which produce too much polarity. If M^2 is depressed, and the current of pole B is creating too much polarity in magnet H , because h^2 is not at the proper point, the shunt-circuit draws off a part of current from B at e , until the neutralization is as complete as possible. The small rheostat in this shunt serves to regulate its resistance according to the changes which may occur in different parts of the circuit. This shunt itself is not new; but I believe it to be new to use it, as I do, in securing a neutralization of currents in the electro-magnet by drawing off an excess of electricity.

I believe that opposing currents of batteries of the same line-circuit is not new. I believe that a key with a ground-wire is not new; but I believe to be new, and I claim as my invention, and desire to secure by Letters Patent—

1. The method of duplex telegraphing, substantially as described, by localizing or short-circuiting the main battery at the sending-station, thereby preserving the magnetic equilibrium in the signaling-instrument of that station, and allowing the battery of the receiving-station to there exert its full force in recording or indicating signals, substantially as herein described.

2. In combination with a normally-closed telegraphic line having main batteries, one at each terminal, connected to the line in opposition to each other, open-circuit single contact-keys M M^2 and branch circuits N N^2 , connected to the relay-magnets at a suitable point, the closing of the said keys short-circuiting or localizing the battery of the sending-station through the proper proportion of the coils of the relay, substantially as set forth.

3. In combination with a relay-magnet having its layers exposed for connection to key, and for approximate adjustment, as described, the shunt-circuit M and rheostat c , substantially as and for the purposes set forth.

4. In combination with the normally-closed line, having the branch circuits h h^2 and open-circuit single contact-keys, and opposed batteries, as described, the battery-reversers and closed-circuit keys, substantially as set forth.

5. The combination, at an intermediate or way station, with the main line of a duplex telegraph, of the open-circuit key P and branch circuit i , connected to the relay between the terminals, the depressing of the key closing independent circuits for both terminal batteries, giving signals to both sides of the way-

station in single transmission, or forming a duplex line with one terminal, substantially as described.

GEORGES D'INFREVILLE.
